UNITED STATES PATENT OFFICE.

GEORGE J. SEISS, OF TOLEDO, OHIO.

MECHANICALLY-ACTUATED HORN FOR BICYCLES, BOATS, &c.

1,344,724.

Specification of Letters Patent. Patented June 29, 1920.

Application filed April 15, 1918. Serial No. 228,533.

To all whom it may concern:

Be it known that I, GEORGE J. SEISS, a citizen of the United States, residing at Toledo, in the county of Lucas and State of Ohio, have invented a certain new and useful Improvement in Mechanically-Actuated Horns for Bicycles, Boats, &c., of which the following is a specification.

My invention relates to that class of alarm signals which employ a vibrating diaphragm actuated by the rotation of a toothed wheel, the teeth of which engage a wearing piece secured to the center of the diaphragm.

My invention has for its object to provide a construction for a device of this character which will permit the assembling of the entire operating mechanism before it is placed in the body of the horn, and has for its further object to provide a bracket for the horn which will not only support the horn rigidly, but when secured to the horn, will operate to lock the mechanism supporting frame, horn and bracket, rigidly together.

My invention has for its further object to provide means which will prevent the rattle of the actuating rod, and has for its further object to provide means to prevent water from entering the interior of the horn through the opening in which is mounted the actuating rod.

Other objects will appear from the hereinafter contained description.

My means of accomplishing the foregoing objects may be more readily understood by having reference to the accompanying drawings, which are hereunto annexed and are part of this specification, in which:

The figure is a vertical sectional view of a horn constructed in accordance with my invention.

In these drawings the gear segment 23 is mounted so that its teeth engage the wear piece 12, mounted in the diaphragm 11. The segment 23, is carried by the pivot pin, which in this construction is secured in position by an upwardly extending portion 60, of a clamping device 61, which is formed of two parts, 62 and 63, bent into a square and adjustably secured together by means of a bolt 64, and wing nut 65. The upper portion 60, of the clamping device 61, has a punched-out loop 66, which is adapted to enter an opening cut in the rear wall 67, of the horn body, and forms a bearing for the pivot pin. The member 60 is also provided with two tongues 71 and 72 which are inserted in

perforations in the wall 67, and are then bent or clenched down against the wall, thus insuring a firm and rigid connection. In this form of construction, I mount a small coil spring 68, outside of the horn body and intermediate the button 29, the spring 68, operating to hold the segment 23, normally in the position shown in the drawing. This makes a very simple and inexpensive horn, but which is very satisfactory as an alarm for bicycles, etc.

It will be apparent from the above description that the construction set forth fully attains the objects hereinbefore set forth. But the specific description, as well as the drawings, are only to show a preferred form of construction and I do not wish to be understood as limiting myself to the same, as many changes in details may be within the scope of my invention, as set forth in the appended claims.

Having described my invention what I regard as new, and desire to secure by Letters Patent of the United States, is:

1. In a signal, a hollow body, a diaphragm therein, a wear pin in the diaphragm, a toothed segment, a pivot at the angle of the segment, means for mounting the pivot in the body to hold the teeth of the segment in engagement with the wear pin as said segment oscillates, an operating bar and means for pivotally connecting the said bar to said segment.

2. The combination with a cup-shaped body portion, a diaphragm closing the open end thereof, a wear-piece in the center of the diaphragm, a gear segment, the teeth of which engage said wear-piece, a pivot secured to the rear wall of the cup-shaped portion on which said segment swings, an actuating rod pivotally secured to said segment adjacent the pivot pin, said rod extending to the exterior of the cup-shaped portion, a button on the end of said rod, a cushion-spring intermediate the button and the wall of the body portion, said pivot pin being held in position and journaled in a loop member on an upwardly extending portion of a clamping device, the lower part of which is formed into a square made of two parts, means to adjustably secure the two said parts together and means to rigidly attach said upwardly extending portion to the rear wall of the cup-shaped body portion.

3. In a signal, a diaphragm, a member

carrying the diaphragm, a wear element carried by the diaphragm, a toothed segment, means for mounting the toothed segment for oscillatory movement with relation to an engagement with the wear element, and means for oscillating the toothed segment.

4. In a signal, a diaphragm, a member carrying the diaphragm, a wear element car-

ried by the diaphragm, a toothed segment, 10 means at a corner of the segment for mounting the said segment for oscillatory movement with relation to and in engagement with the wear element, and means for oscillating the toothed segment. 15

In testimony whereof I have signed the foregoing specification.

GEORGE J. SEISS.
